UNITED STATES PATENT OFFICE

ANNETTE MOUDRY, OF NEW YORK, N. Y.

DESIGN FOR A CUSHION OR PILLOW COVER

Application filed July 7, 1930. Serial No. 36,273. Term of patent 7 years.

To all whom it may concern:

Be it known that I, ANNETTE MOUDRY, a citizen of the United States, residing at New York, in the county of New York and State of New York, have invented a new, original, and ornamental Design for a Cushion or Pillow Cover, of which the following is a specification, reference being had to the accompanying drawing, forming part thereof.

Fig. 1 is a top plan view of a cushion or pillow cover, showing my new design.

Fig. 2 is a bottom plan view of the same.

Fig. 3 is an end view of the same.

I claim:

The ornamental design for a cushion or pillow cover, as shown.

In testimony whereof I have affixed my signature.

ANNETTE MOUDRY.
